CLAIM

The ornamental design for a computer input device, as shown and described.

DESCRIPTION

FIG. 1 is a top perspective view of a computer input device showing our new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is bottom perspective view thereof, showing the strap in an alternate position for use.

The broken lines in the drawings depict parts of the computer input device that form no part of the claimed design. The broken lines and unshaded surfaces shown in the drawings are not claimed.
